Primary Examiner — Elizabeth J Oswecki

(57) **CLAIM**

The ornamental design for a lock box, as shown and described.

DESCRIPTION

FIG. 1 is a front, top, and left side perspective view of a lock box, showing my new design;

FIG. 2 is a top view of the lock box of FIG. 1;

FIG. 3 is a bottom view of the lock box of FIG. 1;

FIG. 4 is a front side view of the lock box of FIG. 1;

FIG. 5 is a back side view of the lock box of FIG. 1;

FIG. 6 is a left side view of the lock box of FIG. 1; and,

FIG. 7 is a right side view of the lock box of FIG. 1.

The broken lines showing a keyhole in FIG. 1 and FIG. 2 are for the purpose of illustrating a portion of the lock box that forms no part of the claimed design.

1 Claim, 4 Drawing Sheets(56)
